DESIGN FOR A BOTTLE

Marc A. Byrd, Saegertown, and Frank La Bounty, Edinboro, Pa.

Application January 15, 1944, Serial No. 112,244

Term of patent 3½ years

(Cl. D58—8)

To all whom it may concern:

Be it known that we, Marc A. Byrd and Frank La Bounty, citizens of the United States, residing, respectively, at Saegertown, county of Crawford, State of Pennsylvania, and Edinboro, county of Erie, State of Pennsylvania, have invented a new, original, and ornamental Design for a Bottle, of which the following is a specification, reference being had to the accompanying drawings, forming a part thereof.

In the drawing:

We claim:

The ornamental design for a bottle, substantially as shown.

MARC A. BYRD.
FRANK LA BOUNTY.
